ELECTRIC FOOT VIBRATOR AND VIBRATORY SEAT COMBINATION

Willis L. Breshears, 1505 Ave. H, Levelland, Tex.

Filed Dec. 29, 1959, Ser. No. 58,846

Term of patent 3½ years

(Cl. D83—1)

Fig.1

Fig.2

Fig.3

Fig.4

Fig.5

Fig. 1 is a front perspective view showing the top of an electric foot vibrator and vibratory seat combination embodying my new design;

Fig. 2 is a rear elevational view thereof;

Fig. 3 is a front elevational view thereof;

Fig. 4 is a left side elevational view thereof, the right side not shown being substantially the same as the left side shown; and

Fig. 5 is a top plan view thereof.

I claim:

The ornamental design for an electric foot vibrator and vibratory seat combination as shown and described.
